COMBINED SWITCH AND END COVER THEREFOR

Kazuma Tateisi, Kyoto-shi, Japan, assignor to Tateishi
Denki Kabushiki Kaisha, Kyoto-shi, Japan

Continuation of design applications Ser. No. 67,119 and
Ser. No. 67,121, Oct. 17, 1961. This application Mar.
31, 1964, Ser. No. 79,373

Term of patent 14 years

(Cl. D26—13)

PAGE 3

Fig. 7~

Fig. 6~

Fig. 10.Fig. 9.Fig. 8.FIG. 1 is a perspective view of a combined switch and end cover therefor, showing one form of my new design wherein the element projecting upwardly from the top of the switch casing is disc-shaped;

FIG. 2 is a perspective view of the switch shown in FIG. 1 with the end cover removed;

FIG. 3 is a rear elevational view of the switch shown in FIG. 2;

FIG. 4 is a front elevational view of the switch shown in FIG. 2;

FIG. 5 is a side elevational view of the switch shown in FIG. 2, the opposite side being substantially a mirror image thereof;

FIG. 6 is a perspective view of a combined switch and end cover therefor showing another form of my new design wherein the element projecting upwardly from the top of the switch casing is annular-shaped;

FIG. 7 is a perspective view of the switch shown in FIG. 6 with the end cover removed;

FIG. 8 is a rear elevational view of the switch shown in FIG. 7;

FIG. 9 is a front elevational view of the switch shown in FIG. 7; and

FIG. 10 is a side elevational view of the switch shown in FIG. 7 the opposite side being substantially a mirror image thereof.

An essential feature of my design is a switch comprising a rectangular casing, having projecting from one side or end thereof a discoid or annular projection having a diameter substantially equal to the width of the side from

which it projects, and having extending from a different side or end thereof a tubelike projection having a radius relatively one half the width of the end or side from which it projects and a length approximately equal to the longest dimension of said rectangular casing, said projection being provided with an end cover.

This application is a continuation of my two copending applications Serial Numbers D. 67,119 and D. 67,121 filed October 17, 1961, abandoned subsequent to filing this application.

I claim:

The ornamental design for a combined switch and end cover therefor, substantially as shown and described.
